UNITED STATES PATENT OFFICE

FREDERICK W. BURGER, OF NILES, MICHIGAN, ASSIGNOR TO CLARK EQUIPMENT COMPANY, OF BUCHANAN, MICHIGAN, A CORPORATION OF MICHIGAN

DIE MECHANISM FOR CONSTRUCTING METALLIC WHEELS

Application filed April 19, 1926. Serial No. 102,894.

The present invention relates to die mechanism for constructing metallic wheels, and particularly wheels of the spoke type.

In prior application Serial No. 33,657 filed on May 29, 1925, by myself and Edmund C. Mogford, we disclosed an improved construction of metallic wheel, and method of making the same. This wheel is of the spoke type and is built up or assembled from two main parts—a cast hollow spoke structure and an outer rim consisting of a steel band. As fully described in the aforesaid application, these two units are rigidly joined together by pressing different portions of the band into interlocking engagement with the ends of the hollow spokes.

The present invention pertains to the die mechanism for performing this pressing operation, and has as its general object to provide an improved construction of die mechanism by which this operation can be performed accurately and expeditiously.

One of the more specific objects of the invention is to provide an improved construction of stationary die or spoke supporting means which can be readily opened for quickly shifting the wheel to successive operating positions; and which, when in its closed position, is firmly held in engagement with the spoke by the pressure incident to the pressing operation.

Another object is to provide an improved construction of resilient wheel supporting means located between the two sections of the stationary die, on which supporting means the wheel can be revolved for presenting the different portions thereof to the above pressing operation.

Other objects and advantages of the invention will appear from the following description of a preferred embodiment thereof. In the drawing illustrating this embodiment:

Fig. 1 is a side elevational view of the present die mechanism, a portion of the two

stationary die members being broken away.

Fig. 2 is a front elevational view of the same, the front supporting or die member being broken away.

Fig. 3 is a detail sectional view illustrating the manner of supporting the spoke in the stationary die means, and

Fig. 4 is a similar view showing the upper pressing die down in the operation of pressing a portion of the rim into the end of one of the hollow spokes.

The present die mechanism is mounted on a base plate 6 which constitutes a support for all of the die parts entering into the present construction. From this base plate rises a standard 7 which constitutes one part of the female supporting die 8, as will be presently described. Bolted to the rear of this standard 7 is a curved arm 9 which carries a bearing 11 at its forward end. The reciprocal plunger or male die 12 is guided in this bearing 11, the upper end of this movable die having an enlarged head 13 through which pressure is applied to this die member from any suitable power press, such as a hydraulic press. A spring 14 is interposed between the bearing 11 and the head 13, and this spring raises the movable die after the performance of each pressing operation.

The female supporting die 8 comprises two cooperating die portions 15 and 16 adapted to engage over the sides of the wheel spoke for peripherally supporting the spoke structure in the pressing operation, and cooperating with the male die 12 to accomplish the desired result of firmly securing the rim upon said spoke structure. The die portion 15 is stationary, constituting an integral part of the standard 7, and the die portion 16 is movable relative thereto, constituting an integral part of a hinged arm 17. This construction forms in effect a split die one part of which is stationary, and the other part of which is capable of being re-

50

tracted from the wheel spoke in order that the wheel may be rotated for presenting another spoke to the pressing operation. The hinged arm or die member 17 has pivotable movement on a pivot shaft 18 which pivotally joins this arm to the base plate 6. Two spaced pivot ears 19 extend from the lower edge of the arm 17 and engage over the outer sides of pivot lugs 21 extending 10 upwardly from the base, the pivot shaft 19 passing through alined holes in the ears 19 and lugs 21. As will hereinafter appear, this point of pivotal support for the movable section of the female die results in the 15 reaction pressure incident to the pressing operation thrusting or forcing this movable section of the female die into firm gripping engagement with the wheel spoke. At the same time, as will be more fully explained 20 later, the spoke structure is peripherally supported by the female die members during the pressing operation. A suitable handle 22 is secured to the front side of the die member 17, by which this hinged die member can 25 be swung out of operative position to release the wheel in order that it may be rotated between successive pressing operations.

The wheel structure upon which the present die mechanism is intended to operate 30 consists of a hub and spoke unit 24 and a rim 25, both of these units being illustrated in dotted lines in Fig. 2. The hub and spoke structure 24 is cast as an integral unit, the spokes 26 being hollow and provided at 35 their outer ends with pads or laterally extended seats 27 adapted to receive the rim 25. The unitary casting 24 that constitutes the hub and spokes is generally made either of steel or malleable iron, and the rim 25 is a steel band of the usual form, preferably 40 of the demountable type. As best shown in Figs. 3 and 4, the outer ends of the hollow spokes are chamfered or beveled as indicated at 28, forming a tapered depression or seat 45 in the outer side of the pad 27, and the pad 27 joins the spoke 26 through a curved flare or filet portion 29 which strengthens the pad 27 and upper end of the spoke. Prior to being presented to the present die mechanism the spoke structure 24 and rim 25 are 50 rigidly joined by pressing the spoke structure laterally into the rim in a suitable power press, so that the wheel comes to the present die mechanism as an assembled 55 unit. In this die mechanism the reciprocable pressing die indents or presses portions of the web of the rim 25 down into the tapered openings 28 in the ends of the spokes as clearly shown in Fig. 4.

60 Referring again to the female die which supports the spoke structure, and firmly holds the particular spoke being operated upon during this pressing operation, the two die portions 15 and 16 have opposing die 65 surfaces 31 and 32 in which are formed ver-

tically extending depressions 33 and 34, tapered to embrace the opposite sides of the wheel spoke 26. The upper surfaces 35 of these die portions are preferably curved concentrically with the curvature of the rim 25. 70 The upper ends of the depressions 33 and 34 are flared outwardly as indicated at 36 to receive the flare 29 formed in the underside of each pad 27 when the two sections of this stationary die are closed over the 75 sides of the spoke 26. The opposing faces 31 and 32 may contact, as illustrated in Fig. 1 or they may be constructed so that a slight space will be maintained therebetween during the pressing operation. In either 80 case the female die provides a peripheral support for the spoke structure, and cooperates with the male die to accomplish the desired indentation of the rim and a close and firm engagement of the indented portion 85 with the spoke end.

When the pressing die 12 engages the rim 25 it presses the metal of the rim down into the tapered opening 28, the lower end of the die 12 being correspondingly tapered as indicated at 38 so that an even thickness of metal will be forced down into the open end 90 of the spoke. This "pressing" operation may consist in drawing the metal down into the open end of the spoke, as shown in 95 Fig. 4, or it may consist in punching the web of the rim so that the metal is extruded or forced down into the end of the spoke and an opening left therein in communication with the opening in the hollow spoke, resulting, in either event, in a countersunk portion of the rim engaging in the depression or pocket 28 in the end of the spoke. All of this has been set forth in detail in the co-pending application above mentioned. 100

It will be evident that in this pressing operation the pad 27 and adjacent portion of the spoke 26 will be firmly reinforced by the female die members 15 and 16. The engagement of the pad 27 over the upper 110 surfaces 35 of these die members will support the underside of the pad, and the engagement of the flared neck portion 29 in the flared ends 36 of the recesses will reinforce this part of the spoke against the 115 outward stresses set up in this pressing operation.

Attention is directed to the fact that by virtue of the particular location of the pivotal axis of the movable half of the female die, this die member will be forced into gripping engagement with the wheel spoke by the very pressure set up in the pressing operation. That is to say, by locating the pivot 18 below and to one side 120 of the point of pressure engagement between the plunger die 12 and the work downward pressure applied to the upper end of the die member 17 will force the die face thereof laterally into pressure engagement with the 125 130

- wheel spoke. This avoids the necessity of any latch mechanism between the split halves of the female die and assures that the spoke will be rigidly held between these two halves.
- 5 To facilitate handling of the wheel in bringing the successive spoke ends around into position where they may be operated upon by the plunger die 12 I have provided a resilient wheel support 41 between the two halves of the stationary die. This resilient wheel support preferably consists of a section of spring metal of strap form having its intermediate portion anchored to the 10 base plate 6, as indicated at 42 and having its ends 43 looped back upon themselves to provide spaced resilient surfaces for engaging the lower portion of the wheel. This resilient supporting device normally tends to force the wheel upwardly and thus takes the weight of the wheel off of the stationary die member 15 when the stationary die is open. However, as soon as the pressure of the pressing die 12 becomes effective on the 15 wheel rim 25 the wheel is pressed downwardly against the resilient pressure of this supporting means 41 and the pad and flared neck portion come down into firm engagement with the female die surfaces. By the provision of this resilient wheel supporting 20 means 41 the handling of the wheel unit in the die mechanism is greatly facilitated. Thus, after the performance of a pressing operation over one spoke end, it is only 25 necessary to swing the movable portion 17 of the female die outwardly, whereupon the weight of the wheel is released from the female die portion 15, and thereafter the upper edge of the wheel can be tilted forwardly to free the spoke from the depression 33, and the wheel can then be readily revolved on this resilient supporting means to bring the next succeeding spoke into 30 registry with the depressions 33 and 34.
- 35 While the foregoing description and drawings disclose an embodiment of my invention which I deem preferable, it will of course be understood that the invention is not limited to the specific arrangement 40 therein described and shown, except in so far as claims may be drawn to specific features of arrangement, but includes generically the subject matter of the broader 45 claims.
- 50 What I claim as new and desire to secure by Letters Patent, is—
1. In die mechanism for pressing portions of a wheel rim into interlocking engagement with a hollow spoke structure, the combination of a male pressing die for pressing a solid portion of the rim down into cupped engagement with openings in the spoke structure and female die means adapted to cooperate with said male die and 55 comprising two separable supporting mem- bers adapted to engage over and support the spoke during said pressing operation.
  2. In die mechanism for constructing metallic wheels, the combination of a plunger die adapted to indent portions of the wheel rim into engagement with a hollow spoke structure, and female die means adapted to cooperate with said plunger die, said female die being split into two portions having relative separating movement in a plane extending transversely of the wheel and adapted to receive and support a spoke of said spoke structure therebetween during the 60 pressing operation.
  3. In die mechanism for constructing metallic wheels, the combination of a movable male die adapted to indent portions of the wheel rim into interlocking engagement with depressions in a spoke structure, and a female die cooperating with said male die during the pressing operation, and comprising two relatively movable die members adapted to peripherally support the spoke structure during such operation.
  4. In die mechanism for constructing metallic wheels, the combination of a movable die adapted to countersink portions of the wheel rim into interlocking engagement with pads on the outer ends of a spoke structure, and means comprising two relatively movable members adapted to extend under into supporting engagement with the inner side of each pad during the aforesaid pressing operation.
  5. In die mechanism for pressing portions of a wheel rim into interlocking engagement with a spoke structure, the combination of a stationary supporting member having a depression therein adapted to engage over one side of a spoke, a pivotally mounted supporting member having a cooperating depression therein adapted to engage over the opposite side of said spoke, said pivotally mounted member being movable in a plane extending transversely of the wheel, said supporting members having outer surfaces extending under and having supporting engagement with a pad on the outer end of the spoke, and a reciprocating plunger die for pressing a portion of the 100 wheel rim into interlocking engagement with said pad.
  6. In die mechanism for constructing metallic wheels, the combination of a pressing die for pressing portions of a wheel rim into interlocking engagement with a spoke structure, and a supporting member movable transversely of the plane of the wheel for supporting said spoke structure and adapted to be held in engagement with one of the 105 spokes thereof by the pressure of the aforesaid pressing operation.
  7. In die mechanism for constructing metallic wheels, the combination of an indenting die for pressing portions of a wheel rim 110

into interlocking engagement with a spoke structure, and means for supporting said spoke structure, including a fixed die member and a co-operating movable die member held in co-operative relation to said fixed die member by the pressure of the pressing operation.

8. In die mechanism for constructing metallic wheels, the combination of a pressing die adapted to force portions of a wheel rim into interlocking engagement with a spoke structure, a stationary supporting member for supporting said spoke structure, and a pivoted supporting member co-operating with said stationary supporting member, said pivoted supporting member being pivoted on an axis extending substantially parallel with the plane of the wheel and offset from the line of pressure of said pressing die whereby the pressure exerted thereby is operative to hold said two die members in co-operating relationship.

9. In die mechanism for constructing metallic wheels, the combination of a pressing die for pressing portions of a wheel rim into interlocking engagement with a spoke structure, a stationary supporting member for said spoke structure, a movable supporting member co-operating with said stationary supporting member, and a pivot for said movable supporting member disposed below and laterally of the point of engagement of said pressing die with the wheel whereby the reaction pressure incident to said pressing operation is operative to force said movable supporting member into engagement with said spoke structure.

10. The combination with a pressing die for pressing portions of a wheel rim into interlocking engagement with a spoke structure, of a stationary die member having die surfaces adapted to embrace a portion of each spoke and to engage under a pad at the outer end of the spoke, a co-operating die member having die surfaces for embracing the other side of the spoke and for engaging under said pad, and a pivot for said latter die member whereby said die member may be swung out of engagement with said spoke structure after the completion of a pressing operation, the axis of said pivot being disposed below said die surfaces and laterally of the plane of the wheel whereby the reaction pressure of said pressing operation is operative to force said latter die member into firm engagement with said spoke structure.

11. In die mechanism for constructing metallic wheels, the combination of a pressing die adapted to operate upon the rim of the wheel, a pair of supporting members adapted to engage the spoke structure of the wheel, to hold the same against rotation during the pressing operation, and resilient wheel supporting means on which said wheel

can be revolved between successive operations of said pressing die.

12. In die mechanism for constructing metallic wheels, the combination of a pressing die for pressing portions of the wheel rim into interlocking engagement with a spoke structure, a stationary die member for supporting said spoke structure, and resilient wheel supporting means for yieldably supporting said wheel relative to said stationary die member.

13. In die mechanism for constructing metallic wheels, the combination of a pressing die for pressing portions of the wheel rim into interlocking engagement with a spoke structure, a support comprising two relatively movable portions adapted to support said spoke structure during the pressing operation, and resilient wheel supporting means disposed between the relatively movable portions of said support and on which said wheel can be revolved between successive pressing operations.

14. In die mechanism for constructing metallic wheels, the combination of a pressing die for pressing portions of the wheel rim into interlocking engagement with a spoke structure, an upright standard having supporting surfaces adapted to engage said spoke structure, a pivoted arm having supporting surfaces adapted to co-operate with said first named surfaces for supporting said spoke structure, and resilient wheel supporting means disposed between said standard and said pivoted arm and comprising a section of strap metal having resilient ends adapted to engage the lower part of the wheel rim.

15. In die mechanism for manufacturing metallic wheels, the combination of a pressing die adapted to indent a portion of the rim of a wheel, a pair of supporting members adapted to engage and support the spoke structure of the wheel, to hold the same against rotation during the pressing operation, and wheel supporting means on which the wheel can be revolved between successive operations of said pressing die.

16. In die mechanism for joining the rim and spokes of a wheel, the combination of an outer die adapted to operate upon the outer surface of the wheel rim, an inner die adapted to receive and hold a spoke, said inner die comprising two die portions, members supporting said dies and having relative separating movement in a vertical plane extending transversely of the wheel, for permitting the spokes to be moved successively into operating position between said inner die portions by rotation of the wheel, and means supporting said outer and said inner dies for relative operating movement radially of the wheel.

17. In die mechanism for constructing metallic wheels, the combination of a plung-

er die adapted to indent portions of the wheel rim into engagement with a hollow spoke structure, and supporting means adapted to receive and support the spokes successively, said supporting means comprising a clamping portion pivotally mounted for swinging outwardly from the plane of the wheel, whereby the spokes can be moved successively into operating engagement with said inner die by rotation of the wheel.
